S. F. ANDERSON

HAND TOOL

Filed March 14, 1921

UNITED STATES PATENT OFFICE.

SWAN F. ANDERSON, OF ROCKFORD, ILLINOIS.

HAND TOOL.

Application filed March 14, 1921. Serial No. 452,080.

To all whom it may concern:

Be it known that I, SWAN F. ANDERSON, a citizen of the United States, residing at Rockford, in the county of Winnebago and State of Illinois, have invented certain new and useful Improvements in Hand Tools, of which the following is a specification.

This invention relates in general to hand tools, and while illustrated in the present instance as embodied in a scraping tool, it is capable of embodiment in various other tools, such as cutters, chisels and the like, in which a sharp edged blade instead of a blunt blade, such as shown, is desirable.

In tools of this general character it has been customary to temper the end of the tool shank so that it will, when ground to the desired shape or sharpened, if preferred, present a working edge. Such constructions necessitate an entire shank of a high grade material, and should the working portion or end thereof become broken or mutilated, the entire tool is rendered worthless.

One of the primary objects of my present invention is to provide a tool which shall be equipped with a detachable blade so that should the blade become broken it may be readily replaced by another.

Another feature of my invention resides in the fact that the shank of the tool may be made of cheaper material than the blade, thus reducing the cost of manufacture.

A further object is to provide novel and improved means for detachably securing the blade to the shank so that it may be readily removed therefrom when occasion requires, but will be rigidly and securely locked in position on the shank when desired for use.

A further feature resides in the construction of the blade and the holding means which serves to similarly lock the blade in position and prevents it from slipping upwardly on the shank, the construction being such that the greater pressure applied to the tool the tighter the blade will be locked in position.

Other objects and many of the inherent advantages of my invention should be readily appreciated as the same becomes better understood by reference to the following description when considered in connection with the accompanying drawings.

Referring to the drawings,—

Figure 1 is a perspective view of a tool embodying my invention;

Fig. 2 is a longitudinal sectional view through the outer end of the work tool;

Fig. 3 is a fragmentary perspective view of the outer end of the shank looking upwardly at Fig. 2;

Fig. 4 is a similar view showing the inner face of the holder;

Fig. 5 is a similar view of the lower face of the blade; and

Fig. 6 is a similar fragmentary view of the opposite face of the blade.

Referring now to the drawings more in detail, reference character 7 indicates generally the shank of a tool which is customarily equipped with a handle 8. This shank is preferably flat as shown, and the extremity thereof remote from the handle is tapered toward the end, as indicated by reference character 9.

The blade, indicated generally by reference character 11, is shown in this instance as having a blunt outer or working end 12, which may be slightly curved transversely as shown in Figs. 1 and 5, although the working edge may be straight for certain kinds of work, and in many instances this edge may be sharpened for cutting purposes. Obviously, the shape of the working edge of the blade is capable of wide variation, and the same shank may be used in conjunction with a number of different blades adapted for various purposes and which may be supplied and interchangeably used with such shank if desired. At its opposite end this blade is struck up to provide a projection or lip 13, the purposes of which will be later explained.

The blade is adapted to lie flat against the upper face of the shank 7, Fig. 2, with the projecting lip 13 disposed away from the shank as shown. For purposes of locking this blade in operative position on the shank, I have provided a holder comprising a relatively flat body 14 provided at or near its outer end with clips 15 adapted to embrace the sides of the shank. These lips are inturned in opposed relation as indicated at 16, to engage the face of the shank remote from the blade. Near its outer end the holder is provided with similar clips 17, the opposite sides each having an inturned flange 18, these flanges being inclined relatively to the body 14 at approximately the same angle as the taper 9 of the shank, so that when the holder is slipped over the end of the shank the clip 17 engaged with the

22
 tapered face 9, will serve to draw the holder and shank together so as to snugly clamp the blade 11 in position between the holder and shank with the operative end 12 projecting beyond the shank in position to engage the surface or object to be worked upon.

The inner face of the body 14 is provided with one or more recesses 19 and preferably a series of such recesses are provided, forming in effect, a row of serrations extending longitudinally of the body. When the blade is interposed between the holder and shank the projection 13 at the inner end thereof, engages in one of these serrations 19, thus locking the blade and holder against relative longitudinal movement, and when the holder and blade have been moved longitudinally onto the shank as far as is permitted by the clips 17 the various parts will be rigidly and securely locked together, so that the blade will project in operative position, and no amount of pressure exerted thereon will cause it to move inwardly on the shank, since an interlocking engagement is effected between the projection 13 and one of the serrations 19. Obviously, the greater the pressure that is exerted longitudinally upon the blade, the more firmly the parts will be locked together, but when removal of the blade is desired it can be readily accomplished by simply sliding the holder and blade together longitudinally off the tapered extremity of the shank. While only one of the depressions 19 is engaged at any one time by the blade projection 13, a series of such recesses is preferably provided in order that the extent of projection of the working end of the blade may be varied if desired, and also in order that the device may be accommodated to blades of various lengths, or to the same blade in case it becomes shortened by prolonged use or repeated grindings. It will be observed that the clips 15 and 17 on the blade holder or clamping plate are in the nature of retaining and clamping clips respectively. The clamping clips 17 serve by engagement with the tapering portion of shank to clamp only that portion of the blade confined between said tapered portion of the shank and adjacent end portion of the clamping plate, while the

clips 15 serve merely to retain the serrated end of the plate in operative position against being forced away from the shank by lengthwise pressure on the blade. By reason of this construction, the blade will be positively clamped at one end; the clamping pressure will be in direct proportion to longitudinal pressure on the projecting end of the blade; and by providing the retaining clips, a comparatively long blade may be used.

It is believed that my invention, its construction and many of its inherent advantages will be understood and appreciated from the foregoing without further description, and while I have shown a preferred embodiment, obviously the structural details are capable of wide modification within the scope of the invention as defined in the appended claims.

I claim:

A hand tool of the character described, comprising a flat shank one face of which is tapered at one end, a flat blade having a working edge at one end and a projecting lip at the opposite end, the blade being adapted to lie against the flat side of the shank with its lip disposed uppermost, and a clamping plate adapted to over-lie the blade and provided at one end with clamping clips and at its opposite end with retaining clips, the former of which engage the tapered portion of the shank and the latter, the straight portion thereof, the clamping plate having on its underside a row of serrations spaced longitudinally thereof, the lip on the blade being adapted to engage in any of said serrations when the clamping plate is loosened by movement of the shank toward its tapered end, the clamping plate serving directly to clamp only the blade portion disposed between said plate and the tapered end portion of the shank by end pressure on the projecting end of the blade, which pressure is transmitted through the blade lip to the clamping plate, and the retaining clips serving to hold the serrated end of the clamping plate in operative relation to the blade lip while the clamping plate, blade and shank are in clamping relation.

SWAN F. ANDERSON.
